BOILER WITH REHEATER

Wilbur H. Armacost, New York, N. Y., assignor
to The Superheater Company, New York, N. Y.

Application July 23, 1930. Serial No. 470,021

7 Claims. (Cl. 122—478)

My invention relates to power plants and to methods of operating the same, and more particularly to steam generating plants having steam reheaters, and aims to provide a commercial apparatus and method for steam utilization adapted to improve the heat efficiency and length of life of a steam consuming prime mover.

In a steam turbine installation of 55,000 k.w. capacity using a steam pressure of 1200 lbs. superheated steam is used on the high pressure turbine and the steam then reheated at 400 lbs. pressure for the low pressure condensing turbine. Assuming average temperatures of superheat and reheat, approximately 12,500 k.w. will be generated in the high pressure turbine, and 42,500 k.w. will be generated in the low pressure turbine, or 22½% and 72½% respectively of the total power generated. It will be seen that a more uniform superheat delivered from the steam reheat is more important from an efficiency standpoint than a uniform superheat be delivered from the primary superheater, as the greater percentage of power is generated from the reheated steam.

However, the ordinary plant having a reheat is so arranged that the gases of combustion give up heat to the water-walls in the furnace, to the boiler tubes and to the primary superheater before they do to the reheat. In the above mentioned arrangement of boiler and auxiliary equipment, it will be noted that the steam reheat works under a considerably lower temperature than the primary superheater, due to being located farther away from the furnace and in a low gas temperature zone. The superheat from the steam reheat over a range of ratings therefore has the characteristic of a convection superheater; that is, the superheat falls off rapidly with a falling off of the capacity of the generating unit, whereas the superheat from the primary superheater does not fall off so rapidly due to its being located in a zone of higher gas temperature and at the same time absorbing some heat by radiation. This order of arrangement of primary superheater and gas reheat has been used heretofore on account of giving greater protection to the steam reheat in the starting up and shutting down periods but involves the disadvantages above noted.

It is an object of my invention to provide a steam generating and reheating arrangement and a method of operating the same whereby the steam from the reheat is kept at an approximately uniform temperature with varying loads on the prime mover associated therewith. An advantage associated with this object is that it is also relatively more important to keep the turbine at constant temperature throughout its low temperature section than throughout the high temperature section for the reason that cutting of

the turbine blades by water in the steam is most apt to occur in the low temperature section.

A further object of my invention is to provide a steam generator having high efficiency and arranged to provide ample protection from overheating to a steam reheat associated therewith and to maintain a substantially constant steam temperature at the outlet of the reheat.

The novel features of my invention are pointed out with particularity in the appended claims, but in order that the invention may be clearly understood I will now describe in detail, in connection with the accompanying drawing, an illustrative embodiment of my invention. In said drawing,

The figure is a sectional elevation, somewhat diagrammatic in character, of a power plant in accordance with my invention.

Referring to the drawing more in detail, the power plant therein illustrates a boiler 10 having water cooled furnace chambers 12 and 14, the gases from which, after flowing through the tube bank 16 of the boiler pass over the primary superheater 18 and reheat 20 and pass off to the stack through a flue 22 in which is shown an economizer 24 and an air heater 26. Steam generated in the boiler 10 is taken from drum 28 through pipe 30 and, after passing through the superheater 18 goes through the high pressure section 31 of the turbine 32. Steam leaving high pressure section 31 passes through a pipe 34 to a reheat 20 and thence through pipe 36 to the low pressure section 38 of turbine 32. After passing through section 38 steam passes to the condenser 40.

In order that the steam for the low pressure stage of turbine 32 may be delivered from reheat 20 at an approximately constant temperature, the reheat 20 is placed in a gas flue separate from that containing the primary superheater 18. In the arrangement illustrated, the tubes in bank 16 are inclined somewhat to the horizontal but extend above both the furnace chambers 12 and 14. The combustion gases from the two furnace chambers, however, are prevented from mixing by wall 42 intermediate the two chambers which runs vertically upward to the mid-point of the tubes 16 and is thence continued upward in the form of a baffle 44 which runs up to the level of the top of the reheat 20. The furnace chamber 12, one-half of the tubes of bank 16 and the superheater 18 are therefore in one gas flue, and furnace chamber 14, the other half of the tubes 16 and the reheat 20 in another. The flue 22 connects through the chamber 46 above the upper ends of the superheater 18, reheat 20 and baffle 44 so that the same stack may be used for both furnaces if desired. However, the rate of combustion in furnace chambers 12 and 14 will not be

the same, fuel being burned in chamber 14 only at such rates as is necessary to maintain a substantially constant steam temperature at the outlet 48 of re heater 20. Furnace chamber 12, however, will be operated at such combustion rates as required to furnish steam for the varying loads on turbine 32. For supplying fuel to chambers 12 and 14 I have illustrated burners 50 and 52 respectively, of the type ordinarily employed with pulverized fuel, but I do not limit myself to any particular form of fuel feeding apparatus. It will be seen, however, that the re heater 20 is protected from excessive temperatures by the tubes in bank 16 which extend therebeneath. As, in general, the rate of combustion in chamber 12 is greater than that in chamber 14, or at least reaches higher maximum, I prefer to provide a greater amount of protection against high gas temperatures for the superheater 18 than for the re heater 20, and for this reason I provide beneath superheater 18, in addition to the tubes of bank 16 additional tubes 54 which extend above the furnace 12 but not over furnace 14.

In the arrangement illustrated, tubes 54 connect at their upper ends with the uptake header 56 of the boiler 10, and in order to supply water to the lower ends of tubes 54, I prefer to provide water headers 57, 57 in a masonry pier 58 on which the dividing wall 42 is supported and to extend water wall tubes 60, 60 upwardly from the headers 57 on each side of the wall 60 to connect with the generating tubes 54 at points 62, 62 adjacent the bank 16. It will be seen, therefore, that the tubes 60 not only act as risers for the boiler tubes 54 but also protect the wall 42 as well as increasing the efficiency of the chambers 12 and 14 by supplying radiant water wall surfaces therefore. Preferably the chambers 12 and 14 are provided with additional water wall tubes 64 and 66 respectively, which are connected to the boiler 10 at convenient points by any suitable means.

The upper portion 44a of the baffle 44 which lies above the tube bank 16 and intermediate the steam heaters 18 and 20 is preferably supported independently of the tubes 16 and, for this purpose, I prefer to employ a special set of generating tubes 68 which are shown as connecting at their lower ends with lower header 70 of the boiler 10 and thence running parallel to tubes 16 and above such tubes to the plane of the baffle 44 at which point tubes 68 bend sharply upward and run vertically between heaters 18 and 20 to a point near the roof of the boiler where they are supported by brackets 72 to a beam 74 and are then bent horizontally and run to a connection with the drum 28 at 76. The section 44a is attached to the tubes 68 so that the weight of such section is carried by beam 74 instead of falling on the bank 16. The tubes 68, lying below the re heater 20, add somewhat to the generating surface between the re heater and furnace 14, but there need be only one row of tubes 68 and they may be spaced further apart than tubes 16 and 54 so that their presence does not materially offset the effect of the tubes 54 to equalize the generating surface beneath the steam heaters 18 and 20.

It will be seen that the tubes of bank 16 all operate at high volumetric efficiency for the reason that there are no baffles extending transversely of the flow of the gases to form dead pockets or corners. It will be seen further that the re heater tubes are sufficiently protected from overheating and it will be understood that the steam delivered

from the superheater, while not having as uniform temperature as that delivered by the re heater, does not vary in temperature beyond the limit set by good commercial practice.

While I have described in detail a specific embodiment of my invention, I do not limit myself to the details of the foregoing disclosure and I wish it to be understood in particular that my invention is of sufficient scope in certain directions to include operating the re heater without water tubes between the re heater and the combustion chamber therefor.

What I claim is:

1. The combination of two separate furnaces, a bank of steam generating tubes spanning both said furnaces, means forming separate gas flues for said furnaces extending through and above said bank, a superheater in one of said flues above said bank, a re heater in another of said flues above said bank, and means whereby the one of said flues having said superheater therein has also a greater extent of generating surface there-in than the flue for said re heater. 80

2. The combination as set forth in claim 1 together with two sets of water wall tubes adjacent each other and one exposed to radiation from one furnace and the other to radiation from the other furnace, both said sets of water wall tubes extending beneath the superheater. 90

3. The combination with a boiler having a steam and water drum, a horizontally inclined tube bank, upper and lower headers for said bank and circulators connecting said headers to said drum, of a baffle within said bank and extending upwardly to a point above the same and means for supporting the portion of said baffle above said bank including water tubes secured to said portion and having their upper ends connected to said drum and their lower ends connected to said lower header. 105

4. The combination as set forth in claim 3 together with a re heater on the side of the upper extension of the baffle and between it and the vertical plane including the lower header, and a superheater on the other side of the upward extension of the baffle. 110

5. The combination of two separate furnaces, a bank of steam generating tubes spanning both said furnaces, means forming separate gas flues for said furnaces extending thru said bank and each flue carrying the entire gas flow from one furnace, a superheater in one of said flues and arranged to receive the steam formed in said bank and a fluid heater in the other of said flues and having a heat demand independent of the rate of 120 the heat demand of said bank of tubes. 115

6. The combination as set forth in claim 5 and in which the superheater is in the gas flue having the greater extent of generating surface therein. 125

7. The combination of two separate furnaces, a bank of generating tubes spanning both of said furnaces, means for maintaining the gases from said furnaces separate throughout said bank, a superheater on one side of said separating means and arranged to receive the steam generated in said bank, a fluid heater on the opposite side of said operating means from said superheater and having a heat demand independent of the heat demand of said bank, two water walls between said furnaces composed of tubes having extensions lying beneath the portion of said bank on the same side of said separating means as said superheater. 135
